UNITED STATES PATENT OFFICE.

MERITT HUTTON, OF ST. BENEDICT, PENNSYLVANIA, ASSIGNOR TO REMBRANDT PEALE, OF NEW YORK, N. Y.

MECHANISM FOR HANDLING AND DUMPING TRAINS OF CARS.

Application filed December 28, 1921. Serial No. 525,320.

To all whom it may concern:

Be it known that I, MERITT HUTTON, a citizen of the United States, residing at St. Benedict, in the county of Cambria and State of Pennsylvania, have made certain new and useful Improvements in Mechanism for Handling and Dumping Trains of Cars, of which the following is a specification.

The invention relates to a mechanism or system for handling material-carrying cars, and more particularly to a system, entirely automatic, or under a single man control, for taking the cars from a loaded train, weighing and dumping the cars, and making up the empty train.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a top plan of a track layout and cooperating mechanism constructed in accordance with the principles of the invention;

Fig. 2 is a side elevation of the loaded track, taken substantially on the line 2—2 of Fig. 1;

Fig. 3 is an elevation, with parts omitted, of the track for the empty cars looking at Fig. 1 from the bottom side of the figure;

Fig. 4 is a profile of one cooperating series of gradients for the tracks;

Fig. 5 is a greatly enlarged, central vertical section, taken substantially on the line 5—5 of Fig. 1, showing the cars in the position of Fig. 2;

Fig. 6 is a vertical transverse section, on an enlarged scale, taken on the line 6—6 of Fig. 5;

Fig. 7 is a detached detail view, partly in

section, and greatly enlarged, taken on the line 7—7 of Fig. 8;

Fig. 8 is a fragmentary detail, greatly enlarged, of the switch mechanism shown at the upper end of the car stop at the left hand end of Fig. 5;

Fig. 9 is a top plan, greatly enlarged, looking substantially on the line 9—9 of Fig. 2, that is, it is a top plan corresponding to Fig. 5, with the cars omitted;

Fig. 10 is a fragmentary detail, greatly enlarged, of the automatic starting device for the car dumper shown in the upper central part of Fig. 9;

Fig. 11 is a fragmentary enlarged detail of the joint of the stop lever shown in Fig. 10;

Fig. 12 is a detached enlarged fragmentary detail looking along the line 12—12 of Fig. 9 in the direction of the arrows;

Fig. 13 is a diagrammatic view of the starting and stopping mechanism for the hauling mechanism for the loaded cars;

Fig. 14 is a detached detail view of the workman operated control for the car dumper.

The invention finds one of its main applications in connection with a coal mine, or other mine, although it will be found useful in other places. One of the main objects of the invention is, mechanically and automatically, to take a "trip" or train of loaded cars and feed them one by one over the scales and through the dump and to make up the "trip" or train of empty cars, thereby reducing the number of workmen required on the "dump" or "tipple" of a mine or other working. In practice it is usually advisable to uncouple and to couple the cars by hand rather than by automatic mechanism, and one workman can do this work and no other labor will be required to operate the "dump" or "tipple," although so far as concerns other features of the invention the operation may be entirely automatic, including the uncoupling and coupling.

Other objects and advantages of the invention will be set forth in connection with the detailed description of the illustrated preferred embodiment of the invention, and it will be understood that the entire descrip-

tion is illustrative and not restrictive of the invention.

Referring now in detail to the present preferred embodiment of the invention, the loaded track, or track for the loaded cars, is indicated by 1 and the empty track is indicated by 2, the empty cars after dumping passing from the loaded track to the empty track by any suitable means, and preferably by the automatic gravity switch, commonly designated a "kick-back" 3.

Means are provided by the invention whereby the successive cars of a loaded "trip" or train are supplied or fed forward one at a time, automatically just as they are required, and delivered into the car dumper, and in accordance with one feature of the invention this operation is performed automatically by the mechanism itself.

In the embodied form thereof, an endless chain car-haul 9 runs over guiding and supporting wheels 10 (the rear one not being shown), the forward wheel 10 serving to drive the car-haul in the usual manner. The car-haul 9 is provided with dogs 11 adapted to engage automatically with the successive loaded cars in the train.

In the embodied form of driving means for the car-haul, a suitable motor 12 is connected through a friction clutch 13 to a speed-reducing gearing mechanism 14 (which may be substantially like that in copending application of Kenneth Davis, Ser. No. 553,251, filed April 15, 1922) and through a friction clutch 15, with the shaft 16 of the car-haul driving wheel 10. It will be understood, so far as concerns most features of the invention, however, that any form of driving mechanism may be provided. With the embodied mechanism, the starting and stopping of the car-haul is effected by means of a brake band 17 operating on the gear speed reduction mechanism, the brake band in the automatic operation of the device being controlled and operated by a solenoid 18.

In accordance with one feature of the invention, a weighing scale is provided in the track between the car-haul and the car dumper mechanism, and as embodied, this track scale 24 is dished from the ends toward the center, so that a loaded car on a gentle gradient will run onto the scale and will stop properly centered thereon, to be weighed. Any suitable indicating mechanism 25 for the scale may be provided, and this may be either supervised by a weighing clerk, or may be of the automatically recording type, both types being in common use in work of this class. In the preferred form of the invention, there is a general relation between the grades of different sections of the track and the various mechanisms, which gradients will be later described.

Beyond the scales is a car dumping mech-

anism 27 which, so far as concerns most features of the invention, may be of any desired form or type, but as shown it is of the rotary reciprocating type, the details of the mechanism thereof being omitted, as such car dumpers may be purchased in the market, an example thereof being the dumper manufactured by the Car Dumper and Equipment Company of Grand Crossing, Chicago. In connection therewith, means are provided for supplying the loaded cars to the car dumper and for removing the empty cars therefrom, said mechanism operating either automatically or being workman controlled, as desired.

Referring now to the detailed embodied form of mechanism for controlling the supply of loaded cars to the car dumper (Figs. 1, 2, 5, 6 and 9), this mechanism is shown operated automatically by the car dumper completing the operation of dumping the next preceding car. As embodied, car stops 30 and 31, respectively, are located adjacent to the track, and swing into and out of the path of the front wheels 32 of the loaded car 33. The car stops 30 and 31 are pivoted, respectively, on horizontally-disposed shafts 34 and 35, supported in brackets 36 and 37, mounted upon or adjacent to the tracks 1. The bottom end of the car stop 30 is pivoted to a rod 38, which rod is pivoted to one arm 39 of a T lever 43, which lever is pivotally mounted at 40.

The bottom of the car stop 31 is pivotally connected to a rod 41, the other end of which lever is pivotally connected to the arm 42 of T lever 43. An arm 44 of T lever 43 is pivotally connected by a rod 45 with the core of a solenoid 46. A spring 47 serves to hold the car stops 30 and 31 resiliently in the car-stopping position, as shown in Figs. 5, 6 and 9, and the solenoid 46 is energized to rock the car stops 30 and 31 out of the way to permit the loaded car 33 to pass into the car dumper. Stops 48 and 49 may be used to limit the movement of the lever 43.

In the present embodied form of the automatic control, and in accordance with one feature of the invention, the car stops 30 and 31 are opened to supply a car to the car dumper automatically by the car dumper returning to normal position after completing the dumping of the previous car. As embodied, the solenoid 46 has circuit wires 54 and 55 and 56 and 57, the latter wires connecting to flexible terminals 58 and 59. Carried on the front of the rotary car dumper is a contact plate 60, having one side 61 of conducting metal and the other side 62 of non-conducting material. This is designed to operate with a rotary dumper of the reciprocating type.

That is, when the dumper is making a half-revolution with the loaded car, and is traveling in the direction of the arrow in

Fig. 12, the terminals 58 and 59 will ride along the insulating face of the member 60 and the circuit will remain open. On the return half-revolution of the car dumper, 5 and just before it comes to rest, the member 60, now traveling in the opposite direction to the arrow in Fig. 12, again passes the terminals 58 and 59. The terminals 58 and 59 will now wipe along the conducting face 10 61 of the member 60, thus closing the circuit and energizing the solenoid 46, and thereby rocking the stops 30 and 31 clear from the track 1, and permitting the car 33 to run into the car dumper.

Means are provided for preventing the car stops from moving back to the stop position before the rear wheels of the car 33 have passed, and in the embodied form of such 15 means, a trip lever 65 is pivoted at 66 upon a support 67, the upper part of the lever 65 being shaped so that it will be swung or tripped by the front wheel of the car 33. At its bottom end, lever 65 is pivoted to a rod 68, which rod at its other end is pivoted 20 to one arm of a bell-crank lever 70, which lever is pivoted upon a support 71. The other arm 72 of the lever 70 works alongside a guide or backing plate 73, extending downwardly from the track 1.

On the rod 38 is formed a lug 74 adapted to interlock with the arm 72 of the bell-crank lever, which lever is resiliently pressed against the rod 38 by a spring 75. Thus, when the solenoid 46 swings the car stops 30 and 31 to the open position, lever 72 will snap down behind the lug 74, and is braced against sidewise flexure by the plate 73, and will hold the car stops in the open position against spring 47. When the front wheel 25 of car 33 trips the lever 65, the rear wheels of the car will be clear of the stops 30 and 31, and by the tripping of lever 65, the arm 72 will be swung clear of the stop 74 and spring 47 will swing the stops 30 and 31 back into stop position behind the rear wheels of car 33, and in position to stop the next following car.

In the present preferred embodiment, the gradient of the track at this point is just sufficient for the loaded car 33 to bump the empty car 80 out of the dumper, and as embodied, the advance of the car 33 automatically swings the car stops from in front of the car 80. In the embodied form of such 30 mechanism, stops 81 and 82, which may be substantially the same as or similar to the stops 30 and 31, are provided. Stop 81 is mounted on a horizontal pivot 83, and stop 82 on a like pivot 84. Stop 81 at its lower end is pivotally connected to a rod 85, and rod 85 at its other end is pivotally connected 35 to an arm 87 of a T lever 86, which lever is pivoted at 88.

The lower end of the stop 80 is pivotally 40 connected to a rod 89, which rod at its other

end is pivoted to an arm 90 of the T lever 86. The other arm 91 of T lever 86 is pivotally connected by rod 92, to the core of a solenoid 93. Stops 94 and 95 serve to limit the swing of lever 86, and a spring 96 45 resiliently holds the car stops 81 and 82 in the stop position.

In the embodied form of automatic control of the stops 81 and 82 by the advancing car 33, solenoid 93 is connected to circuit 50 wires 97 and 98, which connect to an on and off switch 99, having an actuating connection 100 to the lever 65. Thus, when the advancing car 33 trips the lever 65, the circuit through wires 97 and 98 is closed, and 55 solenoid 93 is energized, and the stops 81 and 82 are moved out of the path of car 80, which is bumped out of the dumper by the loaded car 33. As the rear wheel of car 33 trips switch 65, it will break the circuit 60 through wires 97 and 98 and permit the car stops 81 and 82 to return to stop position in front of the front wheels of car 33, so far as the mechanism already described is concerned.

Means are provided for insuring the stops 65 and 82 remaining open until the rear 65 wheels of car 80 have passed and for closing them before the front wheels of car 33 have reached the stops, and in the embodied form 70 the mechanism is similar to the holding mechanism for the stops 30 and 31, already described. A lever 110 is pivotally mounted at 111 in position to be tripped by the 75 wheels of the car 80. At its lower end 100 the lever is pivotally connected to a rod 112, which rod is also pivotally connected to one arm of a bell-crank lever 113, pivoted at 114 on the dumper structure.

The other arm 115 of the lever 113 is 105 adapted to snap back of a lug 116 on the rod 85, similarly to the lever 72 and lug 74 in Fig. 6. Lever arm 115 has a backing plate 117, and is pressed against the rod 85 resiliently by spring 118. When the stops 110 81 and 82 are opened, the lever arm 115 will snap down behind the lug 116, and hold the stops 81 and 82 open until the front wheel of the car 80 trips the lever 110, when the stops 81 and 82 will rock back to the stop 115 position behind the rear wheels of the car 80 and in front of the front wheels of the car 33.

Means are provided by the invention for 120 automatically actuating the car dumper, or for optionally actuating it under the control of a workman or attendant. In the embodied form of means for controlling the operation of the dumper, and referring primarily to the automatically operating feature, this is designed to operate when the loaded car 33 comes to rest against the stops 81 and 82 (Figs. 5 to 11, 13 and 14).

The illustrated form of dumper construction and drive comprises two end frame 125

rings 124 and 125 running in suitable guideways mounted on the general structure, such as a series of flanged rollers 126 and 127, although the details of the dumper structure 5 is immaterial, so far as concerns the general features of this invention. The particular rollers 126 and 127 shown in Fig. 9 serve to rotate the dumper. These rollers are fixed on a shaft 128, mounted in suitable bearings 129.

Fixed on shaft 128 is a gear wheel 130, with which meshes a pinion 131, which is driven through any suitable or standard form of clutch 132, from a motor 133. The clutch 132 is shown operated by a lever 134, pivoted at 135, a spring 136 impelling the clutch 132 into driving position. The other end of lever 135 is pivotally connected at 137 to a rod 138, which rod is pivotally connected at 139 to one arm of a lever 140, which lever is pivoted at 141 upon a suitable support 142.

The lever 140 is provided at its outer end with a cam roller 143, and is provided with a one-way spring-joint 144, whereby the lever will be actuated in one direction by a passing cam but will snap idly over the cam when the cam is traveling in the opposite direction. This particular form of device 25 is adapted for use with the reciprocating rotary dumper. On the flange 125 of the dumper is a cam 145, which cooperates with the lever 140 in the manner described and as shown in Fig. 10.

In the embodied form, the spring 136 presses the lever 134 into driving engagement or position for the clutch, and the cam 145 in passing, through lever 140, swings lever 134 to throw the clutch 132 out of driving engagement to stop the dumper. In the embodied form of mechanism for holding the clutch 132 out of driving engagement (that is, in the stop position, while the loaded car is being run into the dumper and the empty car is being run out) a rigid arm 150 is fixed to one arm of the lever 140, and a stop lever 151 is pivoted at 152. The other end of lever 151 is pivotally connected to the core of a solenoid 153, the lever 151 being resiliently pressed into the detenting position by a spring 154.

Wires 155 and 156 connect the circuit for solenoid 153 (Figs 7 and 8) one to a spring-pressed plunger switch 160 mounted in the car stop 81 and the other to a terminal 161, mounted on the car stop. The plunger 160 is longitudinally slidably, and is held resiliently in the position of Fig. 8 by a spring 162. Depending from the rod 160 is a spring contact piece 163, and in the path thereof is a contact 164 connected to the terminal 161. The contact 164 is formed on one of its sides of conducting metal 165, and on its opposite side of insulating material 65 166.

Thus, as a car wheel strikes the rod 160 in coming up to the stop 81 (Figs. 7 and 8), the contact 163, traveling in the direction of the arrow in Fig. 7, will wipe over and past the conducting strip 165 and energize the solenoid 153, and thereby will swing detent lever 151, and spring 136 will throw clutch 132 into driving engagement. This occurs, it will be noted, just as car 33 stops against the stops 81 and 82.

The dumper will then rotate and dump the loaded car 33, and by its own mechanism (not shown) will reverse its direction and bring the dumped car back. During the reciprocation of the dumper with the loaded car, the coaction of the cam 145 and lever 140 is as shown in the dotted line position of Fig. 10, that is, the cam will not cause the lever to throw out the lever 142 and the clutch. On the return movement of the dumper with the empty car, cam 145 will rock lever 144 and throw out clutch 132 against the pull of spring 136, and detent lever 141 will be snapped behind arm 150, and the dumper will be brought to rest in position to receive the next loaded car and to discharge the empty car which has just been dumped.

In the form of dumper control mechanism which is operated by the attendant, a lever is provided whereby the attendant starts the dumper. In said form, the lever 151 is pivotally connected to a rod 175 (Fig. 14), the other end of which rod is pivoted to one end of a bell-crank lever 176, which lever is pivoted at 177, and is acted on by a spring 178, corresponding to the spring 154.

The other end of lever 176 is pivotally connected to a rod 179, and the other end of the rod is pivotally connected to one end of a hand-lever 180, which hand-lever is pivoted at 181. In this case, the attendant, who could be the weighing clerk, or a man employed to uncouple and couple the cars, by actuating the lever 180, would start the dump with a loaded car into motion, instead of its being done automatically by the loaded car 33 striking the stops 81 and 82. Otherwise the operation would be as already described.

Means are provided by the invention for automatically starting and stopping the car-hauler for the loaded cars, so that the train of loaded cars will deliver one loaded car, or advance the loaded cars one car length for each car which is dumped. In the embodied form thereof, the loaded car-hauler is started into action by the car 33 advancing from the position of Fig. 5 into the dumper, and as so embodied, two contacts, 188 and 189, are in the path of the arm 39 of the T lever 43.

The terminals 188 and 189 are in a circuit having wires 190 and 191, which connect to a magnet 192. The magnet 192 has for its

armature a circuit-controlling lever 193, pivoted at 194, and acted on by a spring 195, which holds it in open-circuit position. The lever 193 connects to a wire 196 of the circuit of the solenoid 18, and a terminal 197 connects by a wire 198 to the solenoid 18, a wire 199 completing the circuit to the supply wire.

Means are provided by the invention for holding the circuit of the solenoid 18 closed, to drive the chain hauler for the loaded cars and also means cooperating therewith for stopping the loaded car-hauler after it has traveled a single car length. As embodied, a pin 200 is fixed to lever 193, and a detent lever 201 is pivoted at 202, having at one end a hook 203 adapted to engage the pin 200, and at its other end being pivotally connected by a rod 204 to the core of a solenoid 205.

Wires 206 and 207 constitute the circuit for the solenoid 205. A spring 208 yieldingly impels the hook 203 into position to hold the pin 200. The wire 207 has a terminal 209 and the wire 206 terminates in a lever 210, pivoted at 211, and resiliently held in the open-circuit position by spring 212. The lever 210 is of some form to be closed directly or indirectly by the car hauler and as illustrated, is in the path of movement of the dogs 11, so as to be forced to the contacting position thereby.

The manner of operation of the mechanism just described is substantially as follows:—

As the loaded car 33 runs into the dumper, the circuit of magnet 192 is closed at the terminals 188 and 189, and lever 193 is thereby drawn to magnet 192, thus closing the circuit of the solenoid 18 at 197. This sets the brake 17 and causes the motor 12 to drive the car hauler.

Hook 203 snaps over pin 200 and holds the circuit for the solenoid 18 closed and the motor 12 consequently continues to drive the car hauler. After the car hauler has traveled the required distance, switch 210 is momentarily closed on contact 209, and solenoid 205 is thereby energized, and hook 203 is swung off from pin 200, and the circuit of solenoid 18 is de-energized and brake 17 is released, thereby stopping the drive of the car hauler by the motor 12. The drive mechanism is provided with a brake-band 214 which goes on automatically in alternation with the brake 17 to hold the loaded trip.

In Fig. 4 a series of track gradients are indicated, which in practice have been found advantageous and successful, but it will be understood that said gradients are illustrative and advisable, and are not restrictive of the invention. The diagram of Fig. 4 is projected from Fig. 2, and they can be considered together.

The track along the automatic car hauler is shown level in Fig. 4 and for a slight distance, as for example, say six feet, depending somewhat on the length of the cars used, beyond the point where the hauler automatically disengages from the car, which space is indicated by reference numeral 220. Then for a short distance, say six feet, the track is arranged on an up grade, as indicated at 221, such up grade insuring slack couplings, so that the leading car, which is now being pushed by the next following car, can be readily uncoupled therefrom.

From the end of this slight up grade, the track slopes preferably more sharply downwardly for a short distance, as shown at 222, and the car is pushed therealong from the part 221 of the track by the car behind it, which is being advanced by the car haul 9, and pushes the preceding car 227 off the scale and causes that car to run down to the car stops 30 and 31. From the scale 24 there is a fairly sharp down grade to the entrance of the dumper, along the section 228 of the track. The car stops 30 and 31 are located in this reach or section of the track which section affords temporary storage for a loaded car while it is waiting for the dumper to complete the dumping of the preceding car.

The tracks within the dumper are also slightly forwardly downwardly inclined, being the section or part 229 in Fig. 4, to hold the car securely to the stops 81 and 82. From the dumper there is for a short distance a section 230 on a grade which may be the same as that for the dumper, and from there on the grade will be sufficiently sharp to cause the empty car to run through the "kick-back" and come back on the empty track.

Referring now to the movement of the cars in Fig. 2, the car 225 is being propelled forward along the level track by the car hauler 9, which will shortly automatically pass out of engagement therewith. At this time the car 224 has come into engagement with the car hauler, and any remaining cars in the train (extending to the right from Fig. 2) will be pulled along by the car 224. The car 226 is being pushed by the car 225 and has passed from the level track to the short and slight upgrade section 221. This gives a slack coupling, so that car 226 may be readily uncoupled from car 225. The uncoupling may be effected, if desired, by any suitable or standard automatic coupling, but in practice it is usually found satisfactory to effect the uncoupling by hand.

The horns 31, the scale 24, and the point at which the grade changes between section of track 221 and section of track 222 are related so that the car 227 leaving the scale will, before the chain haul feeder stops, be on the section of track 228 in a position where it will run by gravity to the car stop 130

or horns 31, and car 226 which has been pushing car 227 will be in such a position that it will run ahead to the low point in center of scale and be free from both the

5 car ahead 227 and the car following 225. The chain haul feeder 9 will be automatically stopped as soon as possible after the advancing car 227 reaches the section of track 228 for the gravity run to horns 31.

10 This could be accomplished by having car 227 make the contact to stop the car feeder 9 as soon as the rear wheels are on section 228 of the track or by making the grade on track 228 steep enough so that car 227 will run quickly to the horns. Section of track 222 just before reaching the scales would be 15 very short, or perhaps eliminated entirely.

Just prior to car 227 being pushed forwardly off the scale by car 226, the car 20 dumper has returned to position, stops 30 and 31 have been opened, and car 232 runs down grade onto the dumper, pushing car 233 out ahead of it. Car 233 will run down and through the kick-back on to the empty 25 track.

The empty track is shown of usual construction, having an endless chain car hauler 234, which may be continuously running, and as shown is driven from a motor 30 235, through reduction gearing 236, and may be provided with a slip clutch 237. The empty cars are coupled on this stretch of track to make up the return empty train.

By the invention, a trip of loaded cars is 35 brought to rest on the track with the first car in position relatively to the automatic hauler, and the cars are then fed mechanically over the scale and into the dump and back onto the empty track, the cars being 40 kept under mechanical control substantially at all times. It is advisable to have at least one man to supervise the automatic operation, and in practice it is preferable with the ordinary types of mine car couplers to have this man uncouple and couple the cars.

The sections of down grade in the track 45 are on the one hand sufficiently sharp to insure all the cars, irrespective of their being easy running or hard running, running along at sufficient speed to effect the desired functions or results, and on the other hand, these down grade sections are sufficiently short and are so located that none of the cars, however easy running, will gain sufficient momentum to cause any damage. The cars are kept under mechanical control except for these very short gravity runs, and where these runs are employed the grade is sufficiently steep and on the other hand sufficiently short to effect the advantages just described.

The invention in its broader aspects is not limited to the specific mechanisms shown and described but departures may be made 60 therefrom within the scope of the accom-

panying claims without departing from the principles of the invention and without sacrificing its chief advantages.

What I claim is:

1. The combination with a track for 70 loaded cars, of a car feeder for releasing from a train one loaded car at a time, a car dumper, means for intermittently supplying a car into the dumper and means operating concurrently to release a loaded car 75 from the car feeder to be forwarded toward the dumper.

2. The combination with a track for loaded cars, of a car feeder for releasing from a train one loaded car at a time, a car 80 dumper, means for intermittently supplying a car into the dumper and means operating automatically concurrently to release a loaded car from the car feeder to be forwarded toward the dumper. 85

3. The combination with a track for loaded cars, of a car feeder for releasing from a train one loaded car at a time, a car dumper, means for intermittently supplying a car into the dumper and means operated automatically by the supply of a car 90 to the dumper for releasing a loaded car from the car feeder to be forwarded toward the dumper. 95

4. The combination with a track for loaded cars, of a car feeder for releasing from a train one loaded car at a time, a car dumper, a car stop operable to release a car 100 to supply it to the dumper, and means operating concurrently to release a loaded car from the car feeder to be forwarded toward the dumper.

5. The combination with a track for loaded cars, of a car feeder for releasing from a train one loaded car at a time, a car 105 dumper, a car stop operable to release a car to supply it to the dumper, and means operated automatically by the supply of a car to the dumper for releasing a loaded car from the car feeder to be forwarded toward the 110 dumper.

6. The combination with a track for loaded cars, of a car feeder for releasing from a train one loaded car at a time, a car dumper, a car stop operable to release a car 115 to supply it to the dumper, and means automatically operating concurrently to release a loaded car from the car feeder to be forwarded toward the dumper.

7. The combination with a track for loaded cars, of a car hauler having means for engaging each car in a train, a car dumper in advance of said hauler, and means operated manually or automatically for moving the car hauler forward a car length 120 for each operation of the dumper.

8. The combination with a track for loaded cars, of a car hauler having means for engaging each car in a train, a car 125 dumper in advance of said hauler, and means 130

operating automatically for moving the car hauler forward a car length for each operation of the dumper.

9. The combination with a track for 5 loaded cars, of a car hauler having means for engaging each car in a train, a car dumper in advance of said hauler, and means controlled by the movement of the dumper for moving the car hauler forward a car 10 length by each operation of the dumper.

10. The combination with a track for loaded cars, of a car hauler having means for engaging each car in a train, a car 15 feeder for releasing from a train one loaded car at a time, a car dumper in advance of said hauler, and means controlled by the movement of the dumper operated to release a car from the feeder for each operation of the dumper.

20 11. The combination with a track for loaded cars, of a car hauler having means for engaging each car in a train, a car feeder for releasing from a train one loaded car at a time, a car dumper in advance of 25 said hauler, and means operated by the dumper to release a car from the feeder by each operation of the dumper.

12. The combination with a track for loaded cars, of a car hauler having means 30 for engaging each car in a train, a car feeder for releasing from a train one loaded car at a time, a car dumper in advance of said hauler, and means operated by the dumper for automatically releasing a car 35 from the feeder for each operation of the dumper.

13. The combination with a track for loaded cars, of a car feeder for releasing 40 from a train one loaded car at a time, a car dumper, means for intermittently supplying a car into the dumper, means operating concurrently to release a loaded car from the car feeder to be forwarded toward the dumper, and means operating automatically 45 for releasing the empty car from the dumper.

14. The combination with a track for loaded cars, of a car feeder for releasing 50 from a train one loaded car at a time, a car dumper, means for intermittently supplying a car into the dumper, means operating automatically concurrently to release a loaded car from the car feeder to be forwarded toward the dumper, and means operating 55 automatically for releasing the empty car from the dumper.

15. The combination with a track for loaded cars, of a car feeder for releasing from 60 a train one loaded car at a time, a car dumper, means for intermittently supplying a car into the dumper, means operated automatically by the supply of a car to the dumper for releasing a loaded car from the car feeder to be forwarded toward the dumper, and means operating automatically 65

for releasing the empty car from the dumper.

16. The combination with a track for loaded cars, of a car feeder for releasing from a train one loaded car at a time, a car 70 hauler having means for engaging each car in a train, a car dumper in advance of said hauler, means operated to release a car from the feeder for each operation of the dumper, and means operating automatically for releasing the empty car from the dumper. 75

17. The combination with a track for loaded cars, of a car feeder for releasing from a train one loaded car at a time, a car hauler having means for engaging each car 80 in a train, a car dumper in advance of said hauler, means operated to release a car from the feeder by each operation of the dumper, and means operating automatically for releasing the empty car from the dumper. 85

18. The combination with a track for loaded cars, of a car hauler having means for engaging each car in a train, a car dumper in advance of said hauler, and means controlled by the dumper for moving 90 the car hauler forward a car length for each operation of the dumper, said means including a device for automatically stopping the hauler after said travel of a car length.

19. The combination with a track for loaded cars, of a car hauler having means for engaging each car in a train, a car dumper in advance of said hauler, and means controlled by the dumper and operating automatically for moving the car 100 hauler forward a car length for each operation of the dumper, said means including a device for automatically stopping the hauler after said travel of a car length. 105

20. The combination with a track for loaded cars, of a car hauler having means for engaging each car in a train, a car dumper in advance of said hauler, and means controlled by the dumper for moving the car hauler forward a car length for each 110 operation of the dumper, said means including a device operated automatically by a car for stopping the hauler after said travel of a car length.

21. The combination of a track for cars, 115 means for supplying cars one by one along said track, a track stop for a supplied car, and means for withdrawing the track stop from the path of said car and for causing the supplying means to supply another car. 120

22. The combination of a track for cars, means for supplying cars one by one along 125 said track, a track stop for a supplied car, a car dumper, and means for withdrawing the track stop from the path of said car and for causing the supplying means to supply another car operated by said track dumper dumping a car.

23. The combination of a car dumper, a track leading to the dumper and approach- 130

ing it by a down grade and having an upgrade portion leading to said down grade portion, a car stop for controlling the supply of the cars to the dumper, a feeder for a train of cars located on said upgrade portion of the track and means for advancing the cars a car length when the car stop passes a car to the dumper.

24. The combination of a car dumper, a track leading to the dumper and approaching it by a down grade and having an upgrade portion leading to said down grade portion, a car stop for controlling the supply of the cars to the dumper, a feeder for a train of cars located on said upgrade portion of the track and means for advancing the cars a car length and operated automatically when the car stop passes a car to the dumper.

25. The combination of an automatic car train hauler, means for dumping a car, and means operated by the dumper as it completes the dumping operation for causing said hauler to supply a full car from said train.

26. The combination of a dished scale track, a down grade track leading to the scale, and means for causing a loaded car to run down said track to dislodge a car from said scale.

27. The combination of a car track for loaded cars, car stopping mechanism associated therewith, car dumping mechanism, electro-magnetic means controlled by the dumping mechanism for moving the stopping mechanism to the inoperative position for releasing a car to the dumper, and means on the said car track for moving the stopping mechanism back to the operative position for stopping a following car.

28. The combination of a car track for loaded cars, car dumping mechanism, car stopping mechanism associated with the track, means controlled by the car dumping mechanism for moving the stopping mechanism to the inoperative position for releasing a car, and means operated by the car before it enters the dumper for moving said stopping mechanism back to the operative position for stopping the next car.

29. The combination of a car dumper, a car track for feeding loaded cars to the dumper, car stopping mechanism associated with the dumper, and means controlled by a car as it passes along the track for moving said car stopping mechanism to the inoperative position for releasing a car from the car dumper.

30. The combination of a car dumper, a car track for feeding loaded cars to the dumper, car stopping mechanism associated with the dumper, means controlled by a car as it passes along the track for moving the car stopping mechanism to the inoperative position for releasing a car, and means

operated by the car thus released for moving the car stopping mechanism back to the operative position for stopping the next car.

31. The combination of a car dumper, car stopping mechanism associated with the dumper, a car track for feeding cars to the dumper, car stopping mechanism associated with the car track, means controlled by the dumper for moving the stopping mechanism on the track to release a car, and means controlled by the car thus released for moving the stopping mechanism on the dumper for releasing a car from the dumper.

32. The combination of a car dumper, car stopping mechanism associated with the dumper, a car track for feeding cars to the dumper, car stopping mechanism associated with the track, means controlled by the dumper for moving the stopping mechanism on the track for releasing a car, means controlled by the car thus released for moving the stopping mechanism on the dumper for releasing a car, and means controlled by the movement of the car thus released from the dumper for moving the stopping mechanism on the dumper back to the operative position for stopping the next car.

33. The combination of a car dumper, car stopping mechanism associated with the dumper, a car track for feeding cars to the dumper, car stopping mechanism associated with the track, means controlled by the dumper for moving the stopping mechanism on the track for releasing a car, means controlled by the car thus released for moving the stopping mechanism on the dumper for releasing a car and means controlled by the car thus released for moving the stopping mechanism on the track back to the operative position for stopping the next car.

34. The combination of a car dumper, car stopping mechanism associated with the dumper, a car track for feeding cars to the dumper, car stopping mechanism associated with the track, means controlled by the dumper for moving the stopping mechanism on the track for releasing a car, means controlled by the car thus released for moving the stopping mechanism on the dumper for releasing a car, means controlled by the movement of the car thus released from the dumper for moving the car stopping mechanism on the dumper back to the position for stopping the next car, and means controlled by the movement of the car released on the track for moving the car stopping mechanism on the track back to the position for stopping the next car.

35. The combination of a car dumper, a car track for feeding cars to the dumper, car stopping mechanism associated with the dumper, means for moving the stopping mechanism to the inoperative position for releasing a car from the dumper, and means

- on the dumper controlled by the movement of the car out of the dumper for moving the stopping mechanism back to the operative position for stopping the next car.
36. The combination of car dumping mechanism, a storage track adjacent thereto, car stopping mechanism associated with the storage track, car stopping mechanism associated with the dumping mechanism, and means operated upon the release of a car from the storage track for moving the stopping mechanism on the dumper to inoperative position for releasing a car therefrom.
37. The combination of a track for loaded cars, means for progressing the loaded cars along the track, a car dumping mechanism, a temporary storage track for loaded cars arranged between the first mentioned track and the dumping mechanism, car stopping mechanism associated with the temporary storage track, and means for operating said car stopping mechanism.
38. The combination of a track for loaded cars, means for progressing the loaded cars along the track, a car dumping mechanism, a temporary storage track for loaded cars arranged between the first mentioned track and the dumping mechanism, car stopping mechanism associated with the temporary storage track, and means operated by the dumping mechanism for operating the car stopping mechanism to release a car from the temporary storage track to the dumping mechanism.
39. The combination of a track for loaded cars, means for feeding the cars therealong intermittently, a car dumping mechanism, a temporary storage track arranged between the first mentioned track and the dumping mechanism, car stopping mechanism associated with the temporary storage track, and means for operating said stopping mechanism for releasing a car from the storage track to the car dumping mechanism and for simultaneously operating said car feeding means to deliver another car to the temporary storage track.
40. The combination of a track for loaded cars, a car dumper, a temporary storage track for loaded cars, downwardly inclined toward the dumper and arranged between the dumper and the first mentioned track, car stopping mechanism associated with the storage track, and means for operating said stopping mechanism for releasing a car for delivery by gravity to the dumper.
41. The combination of a track for loaded cars, a car dumper, a temporary storage track for loaded cars, downwardly inclined toward the dumper and arranged between the dumper and the first mentioned track, car stopping mechanism associated with the storage track, means, operated by the car dumper for operating said stopping mechanism for releasing a car from the storage
- track for delivery by gravity to the car dumper.
42. The combination of a track for loaded cars, a car dumper, means for moving the cars along the track, a temporary storage track for loaded cars, downwardly inclined toward the dumper and arranged to receive cars from the first mentioned track, means, controlled by the dumper for releasing a loaded car from the storage track for delivery by gravity to the dumper, and means controlled by the car as it leaves the storage track, for operating said car moving means for delivering another loaded car to the storage track.
43. The combination of car dumping mechanism, power driven means for operating the car dumping mechanism, and means, actuated by a car upon its arrival in the dumping mechanism, for causing the power driven means to operate the dumping mechanism to dump the car.
44. The combination of car dumping mechanism, power driven means for operating the car dumping mechanism, means, actuated by a car upon its arrival in the dumping mechanism, for causing the power driven means to operate the dumping mechanism to dump the car, and means for automatically stopping the dumping mechanism upon its return to normal position, after completion of the dumping operation.
45. The combination of car dumping mechanism, power driven means for operating the car dumping mechanism, means, actuated by a car upon its arrival in the dumping mechanism, for causing the power driven means to operate the dumping mechanism to dump the car, a storage track for loaded cars, car stopping mechanism associated therewith, and means actuated by the return of the dumping mechanism to normal position, operating the car stopping mechanism for releasing a loaded car from the storage track to the dumping mechanism.
46. The combination of car dumping mechanism, power driven means for operating the car dumping mechanism, means, actuated by a car upon its arrival in the dumping mechanism, for causing the power driven means to operate the dumping mechanism to dump the car, means for automatically stopping the dumping mechanism upon the return to normal position, after completion of the dumping operation, a storage track for loaded cars, car stopping mechanism associated therewith, and means actuated by the return of the dumping mechanism to normal position, operating the car stopping mechanism for releasing a loaded car from the storage track to the dumping mechanism.

In testimony whereof, I have signed my name to this specification.

MERITT HUTTON.
